UNITED STATES PATENT OFFICE.

PERCY B. SULLIVAN, OF DECATUR, ILLINOIS.

ACETYLENE-GAS-GENERATING APPARATUS.

1,412,901.

Specification of Letters Patent. Patented Apr. 18, 1922.

Application filed August 14, 1918. Serial No. 249,816.

To all whom it may concern:

Be it known that I, PERCY B. SULLIVAN, a citizen of the United States, residing at Decatur, in the county of Macon and State of Illinois, have invented certain new and useful Improvements in Acetylene-Gas-Generating Apparatus; and I hereby declare that the following is a full, clear, and exact description thereof, reference being had to the accompanying drawings, which form part of this specification.

This invention is a novel apparatus for producing acetylene gas, for use in dwelling houses and the like.

15 The objects of the invention are to provide novel means for automatically feeding the carbide from the hopper when the amount of gas in the bell or holder drops to a predetermined minimum point; also to provide novel 20 means for protecting the carbide feed valve from water of condensation, so that the valve will not become clogged by wet carbide powder; which would interfere with the desired freedom of movement of the feed valve; also 25 to provide a supplemental carbide supply and control valve therefor whereby when the main supply is exhausted the generator may be enabled to operate for a further period of time before recharging.

30 In the appended claim the novel features of construction and combination of parts for which protection is desired are summarized, and I will explain the invention with reference to the accompanying drawings, which 35 illustrate one practical form of apparatus embodying the invention, and an understanding thereof will enable others to adapt and use the same.

In the drawings:

40 Figure 1 is a vertical sectional elevation of a carbide gas generating apparatus embodying the invention.

Figure 2 is an enlarged vertical sectional view of the main carbide hopper and feed 45 valve.

Figure 3 is an enlarged transverse sectional view of the main and auxiliary feed hoppers and their valve operating devices, on line 3—3, Fig. 1.

50 The apparatus indicated in the drawings comprises a water-tight holder or casing 1, which may be of any suitable construction, but is preferably made of metal, and provided with a removable cover 1^a. This casing is preferably buried in the ground and

may if desired be surrounded and reenforced by concrete.

Within this casing is a removable cylinder 2, which is open at its upper end, and its lower end is preferably enlarged or bell shaped and rests upon the bottom of the casing 1.

Preferably removably mounted above and upon the upper end of the cylinder 2 is a main feed hopper 4, adapted to contain carbide, and preferably having an inverted conical bottom 4^a provided with a small opening at its apex for the escape of carbide. This opening is normally closed by a conical self-adjusting valve 5 which is loosely suspended from the lower end of a rod 5^b (preferably by means of a link 5^a loosely connected to the apex or top of the valve and loosely connected to the lower end of the rod 5^b) in such manner that said valve is capable of 75 such universal movement relative to the rod and to its seat that it can readily automatically adjust itself to the seat, as hereinafter explained.

The rod 5^b is preferably suspended from 80 and pivotally connected to one end of a lever 5^c, pivoted at 5^d on a bar 5^d that is suitably secured within and preferably extends across the hopper, and lever 5^c is provided with a weight 5^e on its free end to cause the lever 85 to hold valve 5 normally yieldingly closed. The rod, lever, and weight may be protected from the carbide in the hopper by a suitable radially disposed housing 5^f therein, to prevent the carbide interfering with the free 90 action of the movable parts. Said housing may be connected at top to the bar 5^d, and at its outer end to the wall of the hopper, and at bottom to a bridge piece as 5^g secured to the bottom and within the hopper. The 95 valve rod 5^b projects above the lever 5^c and through an opening 5^h in the top of the housing 5^f.

Within the tank 1 is a movable gas bell 6 which is open at its lower end and encloses 100 the hopper 4 and the upper part of the diaphragm 2. The space within the lower part of the cylinder 2 and the casing 1 is partly filled with water W, and the lower open end of the bell is submerged in such water, and sealed thereby. The upper end of the bell is gas-tightly closed by head 6^a; and the interior of the bell forms a gas retaining chamber in the usual manner.

A supply of carbide is placed in the hop- 110

per 4, and then when the bell is lowered its top 6^a depresses valve rod 5^b and unseats valve 5 which permits sufficient carbide to drop into the water in the diaphragm to produce gas which rises above the water and escapes from the diaphragm into the bell through apertures 2^c in the upper part of the cylinder adjacent the conical lower part of hopper 4.

10 Normally the gas will lift the bell sufficiently to keep its head 6^a out of contact with the upper end of the valve rod 5^b, and the valve will then be held closed by weighted lever 5^c; but as the gas is withdrawn the bell 15 gradually descends, and when the gas becomes nearly exhausted the top of the bell engages and depresses the valve rod 5^b thus opening the valve 5 and admitting more carbide into the cylinder.

20 As the valve 5 is loosely suspended from the rod 5^b, so as to be universally movable, as stated, a very slight movement of the rod 5^b will cause said valve to shift sufficiently to permit enough carbide to escape from the 25 hopper into the cylinder to generate the requisite amount of gas to raise the bell and permit the valve to close. This valve 5 will automatically adjust itself in closing the opening in the hopper, and if a piece of carbide should catch on one side of the valve 30 the valve would tilt so that the side of the valve farthest from such piece of carbide would close against the seat and prevent over-feeding of carbide. If the valve rod 35 is jarred or depressed only very slightly by the bell top the valve will open sufficiently to admit a small quantity of carbide into the container. Thus this automatic self adjusting valve is very sensitive, and practically 40 will admit only such an amount of carbide as is required to maintain the desired supply of gas in the bell; and according to the number of burners which may be in operation at any given time.

45 Attached to the bottom of the hopper adjacent and surrounding the feed valve 5 is an annular outwardly flaring skirt or flange 4^a which depends slightly below the valve 5 and protects it from the water of condensation that usually forms on the sloping exterior bottom wall of the hopper and trickles down toward the valved opening in the hopper; and but for this protector would wet the valve and cause it to clog. This circular 50 conical skirt directs the water away from the valve and valve opening and keeps them entirely dry. This skirt also serves as a support or seat for the hopper, when it is removed from the generator for filling; and 55 this skirt protects the loose feed valve from being accidentally struck and damaged when the hopper is being lifted out of or replaced in the generator.

60 It is desirable to provide an auxiliary supply of carbide for use in case the supply in

70 hopper 4 becomes exhausted before the owner is ready to replenish it, or when it is not convenient to immediately replenish it. For this purpose I place an auxiliary hopper 8 in hopper 4, this hopper 8 being preferably provided with an inverted conical bottom 8^a having an outlet in its apex closed by a valve 8^b, pivoted at 8^c on the adjacent side of the hopper 4 and having a finger 8^d on one end projecting outside of hopper 4 through a 75 small slot 4^e in the side thereof, as shown. The inner free end of valve 8^b may be supported by a bail 8^f attached to the hopper 8^a. The valve 8^b is normally closed. The auxiliary hopper 8 can contain about a gallon of 80 carbide, and should be filled when the hopper 4 is filled, valve 8^b being first closed.

To the inner side wall of the bell 6 adjacent the hopper 8 I attach a rib 6^e, and by 85 partly rotating the bell on its axis the rib 6^e can be caused to engage the outer end of the finger 8^d and open valve 8^b as indicated in dotted lines in Fig. 3. If the carbide in hopper 4 is exhausted there will be a failure of the gas supply to the burners; and if this 90 happens at a time when it is not convenient to refill the hopper 4, (for example at night) the owner can remove cover 1^a, and reach down and partly turn the bell 6 so as to cause rib 6^e to engage and open valve 8^b and 95 allow the carbide in the auxiliary hopper to escape into the main hopper.

At the time the auxiliary feed hopper is 100 opened, the main feed valve 5 at the bottom of the hopper would usually be wide open, and if all the carbide in hopper 8 was suddenly dashed into the water much of it 105 would be wasted before the bell could rise and close the feed; and the splash of the water might cause the carbide and water to foam up against the bottom of the hopper 4 and wet the valve 5 and cause it to clog. To prevent this I make a small outlet in the bottom of the auxiliary hopper and the carbide 110 therein gradually enters the hopper 4 and the supply of carbide to the generator is controlled by valve 5 in the manner above described.

The supply from the auxiliary hopper will 115 enable the apparatus to be used for a few hours or long enough to enable the owner to refill the hoppers 4 and 8. The gas is preferably conducted from the bell 6 to the service pipe S by a connection between the upper portion of the bell and the end of the 120 service pipe in the tank. Preferably this connection is made out of flexible hose 7, one end of which hose is gas-tightly connected to an outlet nipple 6^c on the bell, and the other end connected to the end of the service pipe 125 in the tank as at 7^b, and preferably the points of connection, 6^c and 7^b, are almost diametrically opposite so as to provide a sufficient length of hose 7 between said points to permit the free up and down movements 130

of the gas bell, and the turning thereof to open the auxiliary hopper valve without putting any strain upon the connection 7. This connection between the upper end of 5 the bell and the service pipes being above the water level clogging and choking of the gas outlet is prevented.

What I claim is:

In a carbide gas generating apparatus, the 10 combination of a tank; a bell; a feed hopper within the bell having an outlet; a transverse bar in said hopper; a lever in the hopper pivoted on said bar; a weight mounted on said lever; a rod in the hopper pivoted 15 ally connected with said lever and having one end extending above said lever adapted

to contact with the top of said bell; said bar, lever, and weight being wholly within the hopper; a self-adjusting valve for closing said outlet loosely connected with the 20 lower end of said rod, said rod being adapted to be held normally in raised position by the weighted lever to close the valve, said valve being opened by contact of the upper end of said rod with the bell when the bell 25 is lowered; a service pipe connected with the tank, and a flexible hose connection between the bell and service pipe, substantially as described.

In testimony that I claim the foregoing as 30 my own, I affix my signature.

PERCY B. SULLIVAN.
